(57) **CLAIM**

The ornamental design for a cap as shown and described.

DESCRIPTION

FIG. 1 is a perspective view of a cap showing my present design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The thick broken lines are sewing threads of the cap. The thin broken lines illustrate portions of the cap which form no part of the claimed design.

1 Claim, 7 Drawing Sheets
